No. 686,691.

Patented Nov. 12, 1901.

E. A. HARDISON.

AUTOMATIC CASING PERFORATOR FOR DEEP WELLS.

(Application filed Jan. 2, 1901.)

(No Model.)

UNITED STATES PATENT OFFICE.

EDWIN A. HARDISON, OF LOS ANGELES, CALIFORNIA, ASSIGNOR OF ONE-HALF TO WALLACE L. HARDISON, OF LOS ANGELES, CALIFORNIA.

AUTOMATIC CASING-PERFORATOR FOR DEEP WELLS.

SPECIFICATION forming part of Letters Patent No. 686,691, dated November 12, 1901.

Application filed January 2, 1901. Serial No. 41,876. (No model.)

To all whom it may concern:

Be it known that I, EDWIN A. HARDISON, a citizen of the United States, residing at Los Angeles, in the county of Los Angeles and 5 State of California, have invented a new and useful Improvement in Automatic Casing-Perforators for Deep Wells, of which the following is a specification.

This invention is an improvement upon my 10 automatic casing-perforator for deep wells set forth in Letters Patent of the United States dated May 22, 1900, No. 650,318.

The object of my present improvement is to so construct the casing-perforator that it 15 can be invariably operated to perforate the well-casing exactly where and only where it is desired to perforate and to allow the apparatus to be withdrawn from any point whenever desired without perforating the casing 20 during the act of withdrawal. By means of my present invention I am also able to do away with a portion of the latch shown in my former application, thereby simplifying and cheapening the device, while improving its 25 operation, as above stated.

An important object of my invention consists in so constructing the machine as to dispense with the use of the latch in withdrawing the machine through the casing, for the 30 reason that said latch is liable to breakage and to being clogged up with sand and other material in the well.

The accompanying drawings illustrate my invention.

35 Figure I is a perspective view of my invention descending the well-casing with the parts in position to prevent the perforating-tool from operating while the apparatus is descending. Parts are broken away for clearness of illustration. Fig. II is a perspective view of the apparatus with the parts in the position they assume when the apparatus is being drawn up after having been lowered below the place to be perforated. In this view 40 the parts are shown in position with the means for holding the apparatus extended released ready to allow the body of the apparatus to slide down along the perforating-tool carrier. Portions are also broken away for clearness 45 of illustration. Fig. III is a perspective view of the apparatus with the parts in position for

perforating a casing. The body of the apparatus is broken away more extensively than in the other two views to expose the perforating-tool in operation. Fig. IV is an axial section on line indicated by IV IV, Figs. I and V. Fig. V is a section on line V V, Figs I and IV.

a is the perforating-tool carrier, furnished with a frictional device of any suitable character, as indicated at b, for engagement with 60 the well-casing c.

d is the body of the apparatus. The carrier a is slidably connected with said body d. Suitable means are provided for temporarily preventing the body from sliding down 65 along the carrier. Any suitable means may be employed for this purpose; but in the drawings I have shown a latch e, pivotally connected with the carrier a through the medium of the pivot f, and the latch-guide g, which is fastened to the carrier a by the bolt or rivet h. The pivot f pivots the latch e in a slot i in the latch-guide g.

j indicates a perforating-tool mounted on the carrier a to move laterally and longitudinally of the body d. Said body is furnished with a bent guide k, extending along the body and adapted and arranged to hold the perforating-tool j out of operative adjustment when said tool is at its lower position and to 80 project the tool into operative position when the tool is at its upper position. The guide for this purpose consists in the bent walls of the slot k, which slot at its upper portion inclines toward that side of the body from 85 which the perforating-tool is to project when in operative position, so that when the axle m of the perforating-tool j is brought into the upper portion of the slot the perforating-tool will be brought into position to project beyond the periphery of the body, so as to engage the casing to perforate the same.

1 indicates the outwardly-inclined upper portion of the guide. The lower portion 2 of the guide is arranged parallel with the axis 95 of the body of the tool and extends a distance substantially equal to the length of the top finger or pin 3 of the latch.

4 indicates a socket in the lower end of the body b to chamber the finger 3 of the latch 100 to hold the latch to prevent the body from sliding down along the carrier when the ap-

paratus is at first being lowered through the casing, before starting the perforator into operation.

- 5 *n* indicates a slot extending transversely of the carrier to receive the end of the axle *m*, which carries the perforating-tool *j*. This slot allows the axle *m* to move laterally relative to the carrier-body, thus to bring the perforating-tool *j* into its operative and into 10 its inoperative positions, respectively, and to hold the tool solidly in the desired position.
- 15 *o* indicates the guide in the body to cause the carrier and body to move lengthwise relatively to each other.
- 20 *p* indicates a spring to throw the latch *e* into position to enter a chamber *q* therefor in the body of the apparatus.

In practical operation, when the tool is to be inserted into the well-casing, the frictional 25 device *b* will first be brought into the casing with the finger 3 of the latch inserted into the socket 4 therefor. Then the apparatus will be lowered into the well to the required depth. When the apparatus has reached the 30 lowest desired limit, then the body *d* will be drawn up, thus drawing said body away from the frictional device *b*, and consequently sliding the body upward along the carrier, so long as the friction between the friction device 35 and the casing holds the frictional device from moving and until the axle *m* comes to the lower limit of the guide *k*. During the travel of the axle *m* along the lower portion 2 of the guide *k* the tool *j* will not shift, but will be held so that the points of the perforating-tool will not project to perforate the well-casing. When the apparatus has been raised to bring the tool *j* to a suitable point below where the upper end of the lowest line of 40 perforations is to be, the body *d* will be drawn up and the frictional device *b* will hold the carrier from moving until the finger 3 is withdrawn from the socket 4 and is thrown by spring *p* into line with the chamber *q* therefor. Then the body is lowered, and thus the tool *j* is brought into the position indicated 45 in Fig. III, with the latch 3 drawn up into the chamber *q* in said body and the axle *m* is at the upper end of the oblique portion 1 of the 50 guide, thus throwing the cutters or points of the tool out to engage the wall of the casing. The body *d* is then lowered, thus causing the perforating tool or wheel *j* to perforate the casing until the lower limit for the line of 55 perforations has been reached. Then the apparatus will be drawn up and turned to bring the tool *j* into position for another line of perforations and then again lowered. The opera-

tion just above described will then be repeated until the casing is fully perforated at that 60 level. Then the apparatus will be raised to another level and the operation again performed as before, and so on until the work is done.

What I claim, and desire to secure by Letters Patent of the United States, is—

1. A casing-perforator comprising a perforating-tool carrier furnished with a frictional device for engagement with the well-casing; a body with which the carrier is slidably connected; a perforating-tool mounted on the carrier to move laterally and longitudinally of the body; said body being furnished with a guide extending along the body and adapted and arranged to hold the perforating-tool out of operative adjustment when said tool is at its lower position and inclined upwardly toward that side of the body from which the perforating-tool is to project when in operative position and means for temporarily holding the body from sliding down the carrier when the apparatus is descending with the frictional device in contact with the well-casing. 75

2. The combination of the body; a perforating-tool carrier connected with said body to slide therealong and furnished with a frictional device for engagement with a well-casing; a perforating-tool carried by said carrier and having a limited movement transverse 90 said carrier; a latch pivoted to said carrier and furnished with a finger of definite length, said body being furnished with a socket of a given length to seat said finger to hold the carrier in extended position, and said body 95 being also furnished with a guide for said perforating-tool, the upper portion of said guide being inclined upwardly toward that side of the body from which the perforating-tool is to project when in operative position; the lower portion of said guide extending parallel with the axis of the body a sufficient distance to allow the finger to withdraw from the seat in the body when the carrier is in its fully-extended position; and means for withdrawing the finger out of the way of the body 105 when said finger is released from said socket. 100

In testimony whereof I have signed my name to this specification, in the presence of two subscribing witnesses, at Los Angeles, 110 California, this 26th day of December, 1900.

EDWIN A. HARDISON.
